UNITED STATES PATENT OFFICE.

JOSEPH KRAMER, OF MOBILE, ALABAMA.

CARTRIDGE-DISCHARGING ATTACHMENT FOR GUNS.

1,089,000.

Specification of Letters Patent.

Patented Mar. 3, 1914.

Application filed April 15, 1913. Serial No. 761,397.

To all whom it may concern:

Be it known that I, JOSEPH KRAMER, citizen of the United States, residing at Mobile, in the county of Mobile and State of Alabama, have invented certain new and useful Improvements in Cartridge-Discharging Attachments for Guns, of which the following is a specification.

My invention relates to automatic magazine firearms, in which the recoil following the explosion of the cartridge is used to operate the breech mechanism, this type of firearm being illustrated and described in Patent No. 768,665, granted to Thomas C. Johnson, August 30, 1904. In guns of this class, there is provided a spring actuated cartridge carrier disposed within the gun frame and having a prolongation extending over the loading opening. This carrier is normally disposed in alignment with the magazine but may be forced inward to disclose the opening to the magazine. When so forced inward, it forms a track whereby cartridges are guided into the opening of the magazine or out of the opening when the cartridges are being withdrawn. To permit either the introduction of shells or the expulsion of the shells, it is necessary to force the carrier inward. In order to withdraw unexploded shells from the magazine, it is necessary to insert the finger through the loading opening and hold the cartridge carrier forced inward. This allows the magazine spring to force the cartridges in the magazine rearward or into the loading chamber. As the finger is used to hold the carrier inward, and as the magazine spring is relatively strong, the foremost cartridge will be projected rearward against the finger with considerable force and the cartridge will bruise and lacerate the finger. Where many cartridges are being thus removed from the magazine, the bruising action will be considerable.

The primary object of my invention is to avoid the objection above noted by providing means whereby the carrier may be forced inward without the necessity of inserting the finger in the loading opening and holding the cartridge carrier inwardly pressed, so that the finger need not be disposed in the way of the cartridge as it is ejected from the magazine.

A further object is to so dispose the means for forcing inward the cartridge carrier that it may be operated from the exterior

of the gun and in most convenient position to the hand of the operator.

Another object of the invention is to provide the barrel with a balancing weight disposed along the entire extent of the barrel on its upper side and affording a flat and a relatively wide sighting surface as well as properly balancing the gun, the upper face of the balancing weight disposed upon the barrel being approximately flush with the barrel extension.

A further object of the invention is to provide an extension to the magazine whereby more cartridges may be carried within the magazine than is usually possible in guns of this type.

Other objects will appear in the course of the following description.

My invention is illustrated in the accompanying drawings wherein:

Figure 1 is a perspective view of a gun constructed in accordance with my invention. Fig. 2 is an elevation of a portion of a gun constructed in accordance with my invention, the gun frame and a part of the fore stock being broken away to show the internal mechanism. Fig. 3 is an underside plan view partly in section of my improved gun, the magazine being shown in section.

Corresponding and like parts are referred to in the following description and indicated in all the views of the accompanying drawings by the same reference characters.

In these drawings, 2 designates the gun stock and 3 the barrel. 4 designates the gun frame and 5 the forestock. All these parts are of the usual construction.

Disposed between the barrel and the gun frame and forming part of the latter, is the barrel extension 6. The gun frame forms a casing inclosing the receiving chamber 7. Formed within the fore stock and extending forwardly beyond the fore stock is the magazine 8. Between the trigger guard frame 9 and the fore stock, and formed in the bottom of the gun frame, is the loading opening 10 through which cartridges may be placed in order to fill the magazine. Disposed within the gun frame is the cartridge carrier designated generally 11. This cartridge carrier is of the usual shape and is provided with the two parallel, forwardly projecting arms 12. The rear portion of the cartridge carrier is angularly disposed to the forward portion thereof, extends rear-

ward and is pivoted to the gun frame by means of trunnions 13. The carrier projects rearward beyond the trunnions 13, and is provided with a transverse stud 14 engaging a spring. This spring will act to depress the forward portion of the cartridge carrier and normally therefore the arms 12 are disposed on each side of the loading opening and in alinement with the lower wall of the 5 magazine. When it is desired to insert a cartridge into the magazine, the cartridge is pressed against the arms 12 forcing the carrier inward until the cartridge is in alinement with the magazine, whereupon the cartridge 10 may be forced forward in the usual manner. After the cartridge has been forced into the magazine, the spring 15 will carry the cartridge carrier back to its normal position and therefore in order to 15 20 move a cartridge from the magazine, it is necessary to force inward the cartridge carrier to the position shown in Fig. 2, whereupon the cartridge will be forced rearward by means of a spring 16 disposed in the forward end of the magazine or within an extension of the magazine. This spring bears at one end against the magazine plug 17 and at the other end against a follower 18 which in turn bears against the foremost 25 30 cartridge.

In order to provide for forcing inward the cartridge carrier without the necessity of inserting a finger into the loading opening 10, I provide a pin 19 which projects 35 downward from the body of the cartridge carrier 11 and extends through an opening in the bottom of the guard frame. On its extremity, the pin 19 is formed with a button or head 20. The pin 19 projects out 40 through the guard frame adjacent to the forward end of the trigger guard and slightly to one side thereof so that when the gun is turned over with the loading opening upward, the head 20 will be convenient 45 to the thumb of the right hand. Preferably the pin 19 is not attached to the cartridge carrier but merely rests against the under face of the cartridge carrier. Thus the pin in no way impedes the free 50 action of the cartridge carrier.

I have found in practice that magazine guns of this type do not hold sufficient cartridges in the magazines and hence I have provided a magazine extension designated 55 21 and supported in alinement with the magazine 8. This magazine extension is formed of a tubular member, the inner end of which is reduced and connected in any suitable manner to the magazine 8, the outer 60 end of which is closed by the magazine plug 17 before referred to. By the use of this magazine extension, I provide for carrying more cartridges than is usually possible and hence add materially to the usefulness of the 65 gun.

The extension 21 would act to throw the gun out of balance and hence I have provided a balancing weight designated 22 which rests upon the barrel and extends the entire length thereof. This balancing weight is made of a relatively flat wide bar, the forward end of which is provided with a sight. The rear end of the balancing weight is flush with the barrel extension 6. I thus provide for not only properly balancing the gun, but also provide a relatively wide flat surface extending the whole length of the barrel which very much facilitates sighting of the gun.

It will be noted that my invention is very simple, can be easily applied to all makes of guns in which a cartridge carrier is used, and that it is of particular convenience where shells are to be removed from the magazine. While I have illustrated a particular type of gun, it is to be understood of course that my invention may be applied to other types and that I do not wish to be limited to the particular form of gun illustrated.

What I claim is:

1. In a gun of the character described, a magazine, a movable cartridge carrier disposed at the entrance to the magazine, and means extending inward from the exterior of the gun and engaging the cartridge carrier, said means being manually movable to force the cartridge carrier inward and having loose contact with the carrier, whereby the carrier may move inwardly independently of the said means.

2. In a gun of the character described, a magazine, a movable cartridge carrier disposed at the entrance to the magazine, and a shiftable pin extending through the under side of the gun and loosely engaging said carrier whereby the carrier may be manually shifted inward whereby said carrier may have movement independently of the pin.

3. In a gun of the character described, a magazine, a cartridge carrier disposed at the entrance to the magazine and pivotally supported at its rear end, a spring normally forcing the forward end of the cartridge carrier outward, and means projecting through the under side of the gun and contacting loosely with the carrier forward of its point of pivotal support whereby the forward end of the cartridge carrier may be shifted inward against the force of the spring said carrier being movable inward independently of said means.

4. In a gun of the character described, a gun frame, a barrel extending from the frame, a magazine extending from the frame beneath the barrel, said frame being formed on its under side with a loading opening, an angular cartridge carrier pivoted in the interior of the frame and having

spaced legs extending toward the entrance of the magazine, a spring normally forcing the forward end of the cartridge carrier outward, and a pin passing loosely through the 5 under side of the gun and contacting at its inner end with the cartridge carrier forward of its pivot whereby the cartridge carrier may be manually moved inward against the force of this spring.

10 5. In a gun of the character described, a gun frame having a loading opening, a magazine extending from the frame forward of the loading opening, a guard frame disposed beneath the rear end of the gun frame 15 and rearward of the loading opening, an angular cartridge carrier pivotally supported adjacent its rear end in the gun frame and

having spaced forwardly extending arms extending above the loading opening, a spring normally holding the forward end of the 20 carrier shifted outward, and a pin loosely mounted in the trigger guard frame, the inner end of the pin contacting with the cartridge carrier forward of its pivot, the outer end of the pin being disposed adjacent the 25 side of the trigger guard and being formed with a head.

In testimony whereof I affix my signature in presence of two witnesses.

JOSEPH KRAMER. [L. s.]
